UNITED STATES PATENT OFFICE.

HERMAN HARDFORD PALMER, OF CHARLESTON, SOUTH CAROLINA.

AUTOMATIC SWITCH.

1,237,949.

Specification of Letters Patent. Patented Aug. 21, 1917.

Application filed December 30, 1916. Serial No. 139,797.

To all whom it may concern:

Be it known that I, HERMAN H. PALMER, a citizen of the United States, and a resident of Charleston, in the county of Charleston and State of South Carolina, have invented a new and Improved Automatic Switch, of which the following is a full, clear, and exact description.

My invention relates to means to automatically operate the switches on railways including street railways and particularly relates to that type of switches adapted to be operated automatically by trips provided on a car or locomotive and arranged to depress switch-operating plungers in the tracks at the sides.

The prime object of the invention is to provide a novel means for locking the switch in any position to which it has been thrown.

A further object of the invention is to provide an automatic switch improved in various particulars with a view to promote reliability of operation and durability.

The invention will be particularly explained in the specific description following.

Reference is to be had to the accompanying drawings forming a part of this specification in which similar reference characters indicate corresponding parts in all the views.

Figure 1 is a plan view of a switch embodying my invention;

Fig. 2 is a transverse vertical section on the line 2—2, Fig. 1, on an enlarged scale;

Fig. 3 is a partial plan view on an enlarged scale, parts being in section;

Fig. 4 is a detail longitudinal vertical section.

My invention is illustrated in connection with a main track *a*, a side track *b*, and switch rails *c*, all of known form. Arranged in the track are plungers designated respectively, 10, 10^a, 10^b, 10^c. These plungers are disposed at the sides of the track in line to be engaged by the trips on the car or train and they are mounted for vertical movement in boxes 11, 11^a which in practice are set in the track at the approaches to the switch. These boxes are arranged transversely of the track, there being one beneath the main track *a* in front of the

switch rails *c* and one extending beneath the main and side tracks distant from the opposite end of the switch.

55

The plungers are adapted to impart movement to rock shafts arranged transversely of the track in the boxes 11, 11^a, one of said shafts 13 being shown in Figs. 3 and 4. The plungers are formed with vertical 60 slots 12 whereby to straddle the shafts. The plungers are connected respectively with the adjacent shaft as at 13 to rock the same, this being effected by rocker arms 14 on the said shafts, the outer ends of the said 65 arms being suitably connected with the plunger to permit vertical movement thereof. In the example shown pins connecting the bars or rocker arms 14 pass through the plungers and through slots 16 in the rocker 70 arms 14.

It will be observed from Fig. 3 that the rocker arms 14 are disposed on the shaft 13 in the box 11 at opposite sides of the shaft so that a depression of the plunger 10 for 75 example will rock the shaft in the opposite direction from a depression of the plunger 10^a and it is to be understood that the shaft in the box 11^a is similarly rocked by the plungers 10^b, 10^c.

80

On the shaft 13, (see Figs. 3 and 4), there are also provided rocker arms 17 at the opposite ends of the shaft, said rocker arms being oppositely disposed so as to be rocked vertically in opposite directions by 85 the rocking of the shaft. The rocker arms 17 are pivotally connected to the lower ends of connecting rods 18, the upper end of each of which is connected with one arm of a bellcrank lever 19, the other arms of which are pivotally connected with operating rods or equivalent elements 20 which are run longitudinally of the track at each side.

Means is provided whereby the longitudinal movement of the rods 20 in either direction will shift the switch rails *c* for which purpose suitable operative connections are provided which in the illustrated example consist of links 22 pivotally connected with 95 the respective rods 20 and each of which is pivotally connected with a bellcrank lever 23 fulcrumed on a block or pillar 24, the opposite arm of the lever being pivoted as 100

at 25 with a link 26, the opposite end of said link being connected as at 27 with the switch bar 21.

Connected with the switch bar 21 at opposite ends also at the pivots 27 are locking bars 28, 29 which extend outward laterally, one of said locking bars as 28 being operatively connected with a signal 30 at one side of the track. The signal 31 at the opposite side may be connected by a link 32 with the adjacent rod 20. The locking bars 28, 29 are moved in transverse slots 35 in blocks 33 having base flanges 34 or the like to secure the same to the track bed. The blocks 33 are also formed with longitudinal throughbores 36 intersecting the slots 35, said bores receiving latch bolts 37 which are in fixed relation to and parallel with the rods 20.

With the described construction a locomotive or car approaching the switch from the left of Fig. 1 can throw the switch rails to the right or left as may be required to permit the train or car to continue on the main track or to take the side track. This is so because the depression of a plunger 10 or 10^a will throw the switch in the proper direction. For example, a depression of the plunger 10^a will throw the switch rails from the position shown in Fig. 1 to permit the locomotive or car to continue on the main track. If, on the other hand, the switch rails *c* are in the position shown in Fig. 1 and the car approaching from the left desires to take the side track *b* then no movement of the switch is required. Again, if the switch rails *c* are positioned to close the side track and continue the main track open, and it is desired to throw the switch to the position shown in Fig. 1, then the plunger 10 will be depressed. Assuming a train is coming from the right of Fig. 1 on the main track, a depression of the plunger 10^c will throw the switch rails from the position shown in Fig. 1 to open the main track. On the other hand, if a car on the side track *b* is approaching the switch and the switch rails are as in Fig. 1, no depression of the plunger 10^c will be necessary but the depression of said plunger will position the switch rails as in Fig. 1 if they are not already so positioned. The depression of any plunger will move the rods 20 longitudinally in opposite directions.

The locking bars 28, 29 are formed with holes 38 to receive the latch bolts 37 and these holes are either oblong or of sufficient size to permit a relative movement of the locking bars and latch bolts when the bolts are in the said holes, so that there may be a slight movement of a locking bar while the latch bolt extends through the same. Comparing the latch bolts 37 at the top and bottom of Fig. 3, the one is in locked engagement while the other is disengaged from

the other locking bar. The latch bolts 37 are moved longitudinally simultaneously with the movement of the links 22 to actuate the locking bars 28, 29 and the switch bar 21, and the proportion of the parts is such that the respective latch bolts will be properly moved relatively to the respective locking bars to cause the switch bar 21 to be moved at the proper time relatively to the movement of the bolts 37 so that the switch will be released, then thrown, and then locked. 75

It will be readily understood that the plungers may be operated by any suitable means and also that the switch, like other switches, may be thrown by hand through the medium of the switch stand or signal stand when the latter is unlocked by a key as is customary with many forms of switches. 80

Having thus described my invention I claim as new, and desire to secure by Letters Patent:

1. In a railway switch, switch rails, vertically movable plungers at each side of the track beyond both ends of the switch rails, shafts supported in the track bed and each ranging across a pair of plungers, connections between the plungers of a pair and the adjacent shaft at opposite sides of the said shaft to rock the latter in either direction by the depression of one plunger or the other, vertically movable elements connected respectively at their lower ends with each shaft at opposite sides thereof to move in opposite directions with the rocking of the shaft in either direction, longitudinally ranging switch-actuating means at the sides of the track, and connections between said actuating means and the switch rails. 95

2. In a railway switch, switch rails, plungers arranged at each side of the track beyond the ends of the switch rails, a switch bar disposed transversely of the switch rails and connected therewith to throw the same, transversely disposed locking bars connected with the respective ends of the switch bar 100 and extending outwardly therefrom, longitudinally ranging rods connected at one end with the respective locking bars, means for moving said rods in opposite directions by the depression of either of said plungers, latch bolts disposed longitudinally of the track and connected with the said rods to move therewith and engage or disengage the said locking bars, links connected at one end with said rods to move therewith, bellcrank levers connected with the opposite ends of said links, and connections between the opposite ends of the bellcrank levers and the switch bar. 115

3. In a railway switch, switch rails, plungers arranged at each side of the track beyond the ends of the switch rails, a switch bar disposed transversely of the switch rails and connected therewith to throw the same, transversely disposed locking bars connected 120

at their inner ends with the opposite ends of the switch bar, longitudinal rods at the sides of the track, means to throw the switch bar and locking bars by the movements of said rods, means to move the rods in opposite directions by the depression of either of the plungers, blocks adjacent to the outer end of each locking bar, the blocks having trans-

verse openings through which said bars move and having bores intersecting the said transverse openings, and latch bolts movable longitudinally with the said rods in the said bores of the blocks, the locking bars having holes through which the said latch bolts may pass.

HERMAN HARDFORD PALMER.
